DOORLATCH

Horace R. Jones, Long Prairie, Minn.

Application November 8, 1934, Serial No. 752,162

1 Claim. (Cl. 292—128)

This invention relates to door latches and the general object of the invention is to provide a door latch of an extremely simple construction which may be readily applied to a door and which is extremely cheap to manufacture.

My invention is illustrated in the accompanying drawing, wherein:—

Figure 1 is a vertical fragmentary section through a door showing my latch applied thereto, the latch being in elevation.

Figure 2 is a horizontal section through a door and door jamb showing the latch in plan view, the handle 20 being in section.

Referring to the drawing, 10 and 11 designate two opposed plates designed to go on each side of a door and be held in place thereon by the half inch bolts 12, carrying thereon the nuts 13. These plates 10 and 11 are slotted for the passage of the lever latch 14, this latch member being pivoted upon a transversely extending pin 15, extending through the latch 14 and extending through openings in the heads of the bolts 12. This pin 15 constitutes a pivot pin for the latch 14.

This latch at one end is curved in one direction, as at 16, to form a handle and at the other end beyond the plate 11, the latch is connected to a retractile spring 17 in turn connected to an end of a bolt 18 which extends through the upper ends of the plates 10 and 11. One edge face of the latch facing the door frame beyond the plate 10 is formed with a notch 19, one wall of which extends inwardly on an incline from the edge face of the latch so that this notch is ratchet-shaped.

Extending over the opposite end of the latch is a guard 20, which is approximately U-shaped and made of a strip of metal, this guard being turned inward at its ends, as at 21, and these ends being apertured for the passage of the bolts 12, the nuts

13 bearing against these inturned ends of the guard.

Coacting with the latch 14 is a keeper plate 22 adapted to be attached to the jamb of the door by screws 23. The end wall of the notch 19 is adapted to engage over the corner 24 of this keeper. It will be seen, of course, that the spring 17 urges the notched end of the latch downward and that as the door closes the latch will ride up over the corner 24 of the keeper 22 and then fall into place 10 behind the keeper, latching the door closed. By lifting the end of the latch 16 or depressing the opposite end of the latch, the door may be opened.

It will be seen that the latch is composed of 15 very few pieces and these very cheaply made and that the latch is very simple to operate.

It will be seen that the guard 20 constitutes a handle for the door and at the same time it acts as a guard to prevent stock from working the 20 latch and opening the door as they do in many makes of latches. When, however, the operator grasps the handle the fingers naturally push against the shank 14 to open the latch.

What I claim is:—

A latching structure of the character described, comprising opposed door clamping plates, bolts passing through the plates and adapted to pass through the door, the plates being slotted, a latch having a shank extending through the slots, a pivot pin upon which the latch is mounted having its ends extending through the bolts, a spring engaging the latch at one end and urging the other end of the latch downward, the last named end of the latch having on its under face a ratchet-shaped notch to engage over a keeper and a U-shaped guard extending around the opposite end of the latch from the notch and having inwardly extending ends through which the bolts pass.
